[57] CLAIM

The ornamental design for an indicator watch, as shown
and described.

DESCRIPTION

FIG. 1 is a front elevational view of an indicator watch
showing my new design;

FIG. 2 is a right side elevational view of the indicator
watch;

FIG. 3 is a rear elevational view of the indicator watch;
FIG. 4 is a left-side elevational view of the indicator
watch; and

FIG. 5 is a bottom plan view of the indicator watch
which is a mirror image of the top plan view of the
indicator watch.
